REFRIGERATING APPARATUS

Edmund F. Schweller, Dayton, Ohio, assignor, by
mesne assignments, to General Motors Corpora-
tion, a corporation of Delaware

Application July 3, 1931, Serial No. 548,584
Renewed December 6, 1933

15 Claims. (Cl. 220—9)

This invention relates to refrigerating apparatus and more particularly to heat insulated cabinet construction.

In the manufacture of insulated cabinets, it has been proposed to use air spaces in the walls thereof to prevent the transfer of heat therethrough. Heretofore such practice has been unsatisfactory for the reason that radiant heat will pass freely through air, and, in addition, the convection currents set up therein will transfer large amounts of heat therethrough. To overcome the transfer of radiant heat it has been proposed to provide a dead air space bounded by a thin bright metal foil or leaf, such for instance as bright aluminum foil. By the term "metal foil" is meant thin leaves of metal either with or without paper backing of such thickness that they can be readily formed to any desired shape. It has been found that these bright metallic surfaces of foil radiate but very little heat, and consequently it is possible to utilize air spaces lined with such bright surfaces in heat insulating cabinets.

Attempts to adapt such thin bright metallic foil to cabinet construction so as to utilize air spaces in the walls thereof for insulating purposes have met with great difficulty. In the first place, this foil is extremely thin and consequently must be so constructed as to prevent rupturing of the foil when such cabinets are subjected to the slam test, a test involving the opening and closing of the cabinet door over prolonged periods of time. In addition, the foil must be so supported within the cabinet wall as to maintain it substantially taut at all times, while at the same time preventing the transfer of heat through these supporting means. Thirdly, care should be taken to prevent the entrance of humid air into the air spaces bounded by sheets of foil, otherwise the moisture therein condenses upon the sheets of bright metallic foil. This may cause the foil to tarnish and to lose some of its reflecting properties which make it particularly valuable for insulating purposes.

It is to such structure that my invention particularly relates, having for one of its objects to provide a cabinet construction having foil insulation, that is, a cabinet capable of utilizing a thin bright metallic foil to advantage, while at the same time eliminating most of its disadvantages.

More particularly, it is an object of the invention to provide an improved cabinet construction the walls of which are composed of independent panels, each panel including a plurality of

frames, each frame defining an air space lined at least in part with sheets of foil; to provide means for preventing transfer of heat from one frame to another; to seal each air space to thereby prevent the ingress of moisture to the spaces between the foil; and to provide constructions of insulated cabinets easy and economical to handle in large scale production.

Further objects and advantages of the present invention will be apparent from the following description, reference being had to the accompanying drawings, wherein a preferred form of the present invention is clearly shown.

In the drawings:

Fig. 1 is a vertical sectional view along the line 1—1 of Fig. 3 embodying one form of the invention;

Fig. 2 is a vertical sectional view of a portion of the cabinet along the line 2—2 of Fig. 3;

Fig. 3 is a sectional view along the line 3—3 of Fig. 2;

Fig. 4 is a vertical sectional view of a portion of a refrigerator cabinet disclosing a modified form of the invention;

Fig. 5 is an enlarged view of an upper corner of Fig. 4;

Fig. 6 is a perspective view of one of the frames together with a set of spacing blocks shown in Figs. 4 and 5;

Fig. 7 is a modified form of frame construction;

Fig. 8 is another modified form of frame construction somewhat similar to Figs. 4 and 5;

Fig. 9 is a sectional view along the line 9—9 of Fig. 10 of a modified form of frame construction employing reinforced cardboard; and

Fig. 10 is a sectional view along the line 10—10 of Fig. 9.

In order to illustrate one aspect of my invention, I have disclosed in Figs. 1 to 3 inclusive a refrigerator cabinet generally designated as 20. This cabinet includes a lower machinery compartment 21 formed by the upright corner members 22 and horizontal cross members 23. The food storage compartment 24 is located in the upper portion of the cabinet. This food storage compartment is preferably but not necessarily enclosed within a one-piece metal liner or inner wall 25. This lining has its front edges secured to horizontal cross beams 27 and similar upright members 28 forming a rectangular door jamb. A convenient way of securing the liner 25 to the door jamb is shown on the drawings comprising nailing or otherwise securing the front edges of the liner 25 to the rectangular door jamb and then securing over the ledges thereof a wooden 55

moulding 30 having a relatively low conductivity. This moulding 30 serves to break the conduction of heat from the exterior of the cabinet to the inner liner 25.

5 Sheets of metal form the outer walls of the cabinet. The sheet metal member 31 is provided for covering the rectangular door jamb. The parts 25, 31, and 33 may be coated with porcelain and in this case chipboard 32 is placed 10 beneath the sheet metal covering for preventing the chipping of the porcelain. A continuous strip of sheet metal covering 33 forms the top and rear outer walls of the cabinet. Over the sheet metal covering 33 a top covering 34 preferably coated 15 with porcelain is provided. A sheet metal covering 35, protected by the chipboard 36, is provided on the side walls of the cabinet. Insulation is provided between the inner and outer walls of the cabinet 20 and more strictly speaking between 20 the inner liner 25 and the outer sheet metal covering 33 and 35. This construction preferably takes the form of a plurality of independent panels, performed before assembling and composed of a plurality of frames, each frame including 25 an air space lined at least in part with this bright metal foil. For example, as shown in Figs. 1 to 3 inclusive, seven rectangular insulating panels, each formed of a plurality of rectangular wooden frames with sheets of bright metallic foil thereon, 30 are provided for insulating the cabinet. The top insulating panel is designated generally by the reference character 40. The bottom insulating panel is designated in general by the reference character 41. The rear insulating panel is generally designated by the reference character 42 while the side insulating panels are designated by reference characters 43 and 44. These panels are similar in general construction. Taking the side panel 44 as an example of this construction, there 35 is provided adjacent the inner liner 25 a rectangular wooden frame 46 to which is attached on the inner side of this frame adjacent the liner 25 a sheet of heavy waterproof material 47 such as waterproof paper. On the other side of this 40 rectangular wooden frame 46 there is attached a sheet of bright metallic foil 48. On the outer side of this sheet of bright metallic foil 48 is attached a second rectangular frame 49 similar to the rectangular wooden frame 46 and to the outer 45 side of the rectangular wooden frame 49 is attached, preferably by a waterproof glue, a second sheet 50 of bright metallic foil similar to the sheet 48. At the outer side of the sheet of bright metallic foil 50 is another rectangular wooden 50 frame 51 similar to the frames 46 and 49. This frame, as well as the frames 46 and 49, is preferably coated on both sides with a waterproof glue in assembling the panel. On the outer side of the rectangular wooden frame 51 is attached, by a 55 suitable glue, another sheet of bright metallic foil 52. On the outside of the sheet 52 of bright metallic foil is a fourth rectangular wooden frame 53 which is attached to the sheet 52 of bright metallic foil by a suitable waterproof glue. On 60 the outer side of the rectangular wooden frame 53 a corrugated sheet of paper 54 is attached by a suitable waterproof glue. These insulating panels are constructed separately as independent units before the assembly of the cabinet. The 65 rectangular wooden frames of each panel are suitably attached together by nails or other means to form the insulating panel which is easily handled and which is readily assembled into the cabinet. By this construction each air space is 70 sealed.

In assembling the cabinet, the framework comprising the four corner uprights 22, connecting cross pieces 23, 31, 38, and parts of the door jamb 27 and 38 are first connected together into a unit. The inner liner 25, after being coated with porcelain, is then attached at its front edges to the top and side members 27 and 28 of the rectangular door jamb. The insulating panels are then placed against the outer side of the inner liner between the frame members and at the rear portions of the cabinet wooden or other non-conducting frame spacing members 56 are attached to the uprights 22 in order to hold the insulating panel 42 in proper position. Similarly the wooden or other non-conducting spacing members 57 are attached to the frame member 27 and the top frame member 38 is holding the insulating panel 40 in proper position. These insulating panels are preferably sealed on their outer faces by a suitable asphaltic substance 58, such as hydrolene, which is poured while hot over the cardboard sheets of the insulating panel and is particularly provided at the corners of the panel for sealing the insulating panels from moisture. This asphaltic substance solidifies within a short time. The corrugated paper acts as an insulator to prevent the heat of the asphaltic substance from distorting the insulating panel or damaging the sheets of foil in any manner. If desired, any other suitable insulating sheet may be used instead of the corrugated paper. Also the corrugated paper may first be suitably coated with a waterproofing substance before the assembling of the frame and after the panel is assembled into the cabinet, the hot asphaltic material need merely be poured around the edges of the panel so that these portions are also sealed to prevent moisture from entering the insulating panels. After this the outer walls of the cabinet are placed over the insulating panels.

The door 59 is similarly insulated by providing rectangular wooden frames having sheets of bright metallic foil thereon and by waterproofing the inner and outer sheets of each panel. By such a construction, moisture is prevented from entering the air spaces provided between the sheets of foil and the sheets of foil are prevented from tarnishing.

In Figs. 4, 5, and 6 a slightly modified form of construction is shown. In Fig. 4 there is shown to 50 illustrate this form, the portion of a refrigerator cabinet 70 having a machinery compartment 71 in its lower portion and a food storage compartment 72 in its upper portion. A machinery compartment is formed by suitable upright members 73 and suitable connecting cross members 74. Attached to the front upright member 73 and the horizontal connecting cross members 74 is a rectangular door jamb frame 75. To the inner portion of the door jamb frame 75 is attached the front edges of the inner liner or wall 76 which surrounds the food storage compartment 72. This inner liner 76 is preferably, but not necessarily, made in one piece.

An outer lining or wall 77 surrounds the inner liner 76 but is spaced therefrom to provide an insulating space between the inner and outer lining. The rectangular attaching member 78 is attached to the rear side of the rectangular door jamb 75 and to this attaching member the front 70 edges of the outer liner 77 is attached. This outer liner 77 may be made in one piece or, as shown in Fig. 4, may be made in two or more pieces. In order to prevent the access of moisture to the insulating space it is necessary that 75

the joints between the several sheets of the outer liner be air-tight. Preferably these sheets of the outer liner may be joined together by a suitable soldering or welding operation. The front edges of both the inner and outer liners 76 and 77 are preferably sealed by suitable sealing compound as shown designated by reference characters 78 and 80.

Between the inner and outer liners or walls 76 and 77, insulating panels are provided. These insulating panels each preferably comprise three rectangular frames, an example of one is shown at 81 in Fig. 6, which frames are separated by wooden or other non-conducting blocks such as is shown at 82 in Fig. 6. These wooden blocks are preferably placed adjacent the corners of the rectangular frames. Sheets of bright metallic foil 83 are attached to both sides of the inner rectangular frames by a suitable waterproof glue and to the inner side of the outer rectangular frame of each of the insulating panels. The frames are all stacked together and fastened by suitable means such as nails. In order to seal the outer perimeter of each of the frames, since the frames in this modification are spaced by the blocks 82, a strip of sealing paper or other suitable sealing substance 84 is attached by a suitable waterproof glue to the perimeter of each insulating panel. This encloses and seals each of the air spaces, preventing convection currents, and also preventing moisture from gaining access to the air spaces and the foil.

It will be seen by inspection of Figs. 4 and 5 that the innermost air space of the back panel in the figures is directly adjacent the inner liner 76 of the food storage compartment 72 and that this air space, excepting for the rectangular baffle members 85, extends to the outer wall of the cabinet. Should the rectangular baffle member 85 not be present, heat would be easily transferred from the outer wall of the cabinet through this air space directly to the food storage compartment 72. By providing rectangular baffle members between the sheets of the back panel, this direct transfer of heat is prevented and especially the convection of air in the innermost air space directly from the inner liner 76 to the outer walls of the cabinet, is prevented. In this way a substantially dead air space prevents the direct transfer of heat from the air spaces adjacent the back wall of the inner liner 76 to the outer wall of the cabinet. The baffle members 85 may be installed very easily during the assembly of the panel by using rectangular panels formed of U-shaped strips of thin stiff cardboard, but other forms of frames such as light wooden or other non-conducting frames may be used, if desired. For symmetry all of the spaces between the sheets of the back wall are provided with the rectangular baffle members. It will be understood that only the several of the innermost air spaces actually require such baffles since the outermost air spaces do not have a direct access to the inner liner 76 of the food storage compartment 72.

The outer liner 77 is covered by galvanized sheet metal covering 89 at the rear of the cabinet, and the top and side portions of the outer liner are covered with the sheet metal covering 99. As in Figs. 1 to 3, the various liners may be porcelainized and chipboard 109 may be placed between the outer covering 99 and the inner liner 77 to prevent the porcelain from chipping. A similar construction is used in covering the door jamb 75. Chipboard 110 is placed upon the outer side of the door jamb frame 75 and in a suit-

able sheet metal covering 111, preferably coated with porcelain, is attached to the door jamb frame 75 over this chipboard. The sides of this covering extend to the inner walls of the door jamb frame 75 and a suitable moulding 112, of a material having a poor conductivity, is placed upon these inner walls so that it covers the front edges of the inner liner 76 and the edges of the outer covering 111 of the door jamb frame which extend into the inner walls of the door jamb frame 75.

The door 112 is similarly insulated. It is provided with a wooden frame 113 which is provided with a sheet metal covering 114 on its inner and outer sides. This covering is preferably coated with porcelain. Between this sheet metal covering on the inner and outer sides of the door is a rectangular insulated panel 115 which is similar to the panels between the inner and outer liners 76 and 77 of the other portions of the cabinet. In Fig. 7 there is shown a slightly modified form of insulating panels from that shown in Figs. 4, 5, and 6. In this form, excepting for the innermost top spacing block 86, the other members of the panel comprise rectangular frames 87 extending around the perimeter of the insulating panels. Sheets of bright metallic foil 88 are attached to the inner adjacent sides of the rectangular wooden frame members 87 and to the innermost side of the innermost frame member 87 and the innermost insulating panel shown in Fig. 7 by a suitable waterproof glue. The frame members 87 and the blocks 86 are attached together by suitable means such as nails.

In Fig. 8 another modification is shown. In this figure there is shown for the purposes of illustration an inner wall or liner 90 and an outer wall or liner 91 of an insulating cabinet. These inner and outer walls are sealed in a suitable manner such as is shown in Fig. 4. Between the inner and outer walls 90 and 91 is provided an insulating panel 92. This insulating panel preferably comprises a pair of rectangular wooden frames 93 and 94. The inner rectangular frame member 94 has sheets of bright metallic foil attached to both sides thereof and the outer frame member 93 has a sheet of bright metallic foil attached to its innermost side and a sheet of paper 96 attached to its outermost side. It has been found that three sheets of foil are sufficient to prevent a high percentage of the heat loss of a refrigerator cabinet through radiation and that the fourth sheet may be of another substance which is lower in cost, such as paper. If desired, however, in order to provide uniformity, and to further reduce the loss due to radiation, all the sheets may be of bright metallic foil. These rectangular wood frames 93 and 94 are preferably spaced from each other by wooden blocks 97 similar to the wooden blocks 82, shown in Fig. 6, and are preferably spaced from the inner and outer liners 90 and 91 by the blocks 98. By employing blocks for separating the frames from each other and from the walls of the cabinet, the heat leakage by conduction through the rectangular wooden frames is greatly reduced. If desired, the insulating panels shown in Fig. 8 may be provided with a sealing strip, similar to the sealing strip shown at 84 in Fig. 5, for sealing the air spaces between the sheets of foil.

In Figs. 9 and 10 another modification is shown. In this modification the rectangular frames forming the insulating panels are made of U-shaped pieces 101 of thin stiff cardboard which are reinforced by suitable zigzag reinforcing

strips 102, better shown in Fig. 10 to make a corrugated cardboard frame. The sides of these rectangular cardboard frames are preferably attached at the corners by a suitable glue or paste, 5 but they may be attached by a suitable clip or staple. The zigzag reinforcing strip 102 is preferably attached to the U-shaped cardboard frames by a suitable glue or staple. Sheets of bright metallic foil 103 are attached to the inner 10 adjacent sides of the rectangular cardboard frame members of the insulating panels shown in Figs. 9 and 10 and sheets of paper 104, preferably of the waterproof type, are placed upon the outer sides of the insulating panel and also around the 15 perimeter of the insulating panel. By placing sheets of strong waterproof paper on the outside of the insulating panel, moisture is prevented from getting into the panel and causing a failure of the cardboard frames and from causing tarnishing of the foil. The strong paper also aids in handling the insulating panels. A suitable sealing strip 105 is provided for sealing the air spaces between the sheets of foil.

In the modifications shown in Figs. 4 to 10, the 20 panels are built up independently and as separate units and are assembled as units as described in connection with Figs. 1 to 3.

By employing an insulation in which the sheets of foil are placed upon frames which are 25 made up into insulating panels for each side of the cabinet, the handling of the foil is greatly facilitated and then the foil can more easily be made by mass production methods. This also facilitates the assembling of the cabinet.

30 While the form of embodiment of the invention as herein disclosed, constitutes a preferred form, it is to be understood that other forms might be adopted, all coming within the scope of the claims which follow.

35 40 What is claimed is as follows:

1. An insulated storage cabinet including inner and outer walls, and insulating means between said inner and outer walls including a plurality of polygon frames, said frames having sheets of 45 bright metallic foil secured to the sides of said frames enclosing air spaces between the sheets of foil, said frames comprising U-shaped strips of cardboard having zigzag reinforcing strips therein.

50 2. An insulated storage cabinet including inner and outer walls, and insulating means between said inner and outer walls including a plurality of polygon frames, said frames having sheets of bright metallic foil secured to the sides of said 55 frames enclosing air spaces between the sheets of foil and polygon baffles in the air spaces between said sheets.

3. An insulated storage cabinet including inner and outer walls and insulation between said inner 60 and outer walls including a plurality of individual polygon frames, sheets of bright metallic foil upon said frames, a plurality of small spacing blocks between said frames for spacing said frames to provide air spaces between said sheets 65 of foil, said frames being fastened together to form a panel, and a sealing strip around the perimeter of said panel for preventing the access of moisture to the exterior of said panel.

4. An insulated storage cabinet having inner 70 and outer walls and insulating means between said inner and outer walls including a plurality of individual polygon frames, said frames having sheets of bright metallic foil thereon, a plurality of small spacing blocks between said frames and 75 a plurality of small spacing blocks on the outer

sides of the outermost frames for spacing said frames from said inner and outer walls.

5. An insulated storage cabinet including inner and outer walls, means forming insulation cavities within said walls, means within said insulation cavities supporting a plurality of sheets of bright metallic foil in spaced relation providing a plurality of air spaces between said sheets of foil, a cover sheet having a relatively low conductivity fitting within one of said cavities and enclosing 10 said sheets of foil within said cavity, and means for sealing the joints between said cover sheet and the walls of the cavity.

6. An insulated storage cabinet including inner and outer walls, insulating means between said 15 inner and outer walls including a plurality of frame members fastened together to form a panel, sheets of bright metallic foil between said frame members, a waterproof sheet sealed to one side of said panel, a sheet covering the other side of said 20 panel, structural members between said inner and outer walls surrounding said panel and a viscous substance sealing the spaces between said panel and said structural members.

7. An insulated storage cabinet including a 25 plurality of structural members joined together to form a cabinet frame, inner and outer walls for the cabinet supported by said cabinet frame, and insulation between said inner and outer walls, said insulation comprising a plurality of insulating 30 frames fastened together to form an insulating panel, sheets of bright metallic foil held between said insulating frames to enclose a plurality of air spaces within said panel, and a viscous substance sealing said panel to adjacent structural 35 members.

8. An insulated storage cabinet including a plurality of structural members joined together to form a cabinet frame, inner and outer walls for the cabinet supported by said cabinet frame, and 40 insulation between said inner and outer walls, said insulation comprising a plurality of insulating frames fastened together to form an insulating panel, sheets of bright metallic foil held between said insulating frames to enclose a plurality of air spaces within said panel, a waterproof sheet sealed to one side of said panel, an insulating sheet on the opposite side of said panel and a viscous substance covering said insulating sheet and the spaces between the panel and adjacent 45 structural members.

9. An insulated food storage cabinet including inner and outer walls, and insulating means between the inner and outer walls including an insulation panel having a plurality of polygon 55 frames stacked together, said panel having sheets of bright metallic foil between the polygon frames, said sheets being held in spaced relation forming substantially dead air spaces therebetween, said panel having a sheet of corrugated cardboard on 60 one side for protecting said bright metallic foil and for strengthening the panel.

10. An insulating structure including inner and outer walls and insulating means between the inner and outer walls including a plurality of individual polygon frames having a plurality of sheets thereon, at least one of the sheets having a metallic heat reflecting surface, and a plurality of small spacing blocks for holding said frames and sheets in spaced relation with gas spaces therebetween. 70

11. An insulating structure including inner and outer walls and insulating means between the inner and outer walls including a plurality of individual polygon frames having a plurality of sheets thereon, at least one of the sheets having a metal- 75

lic heat reflecting surface, and a plurality of small spacing blocks for holding said frames spaced from one of the walls.

12. An insulation panel including a plurality 5 of spaced sheets and a plurality of individual open frame structures between the sheets for holding the sheets in spaced relation with air spaces therebetween, said open frame structures comprising corrugated sheet means with the flutes 10 perpendicular to the spaced sheets and flat sheet portions in contact with and fastened to the corrugated sheet members to form a relatively rigid spacing means.

13. An insulated structure including inner 15 and outer walls for substantially enclosing a space to be insulated, said insulating means including a plurality of independent self-sustaining frames, each of said frames consisting of self-sustaining spacing members arranged in the 20 shape of an unbroken perimeter of a polygon, said frames being superimposed on one another with the spacing members in alignment, flexible material having heat reflecting surfaces secured to 25 said spacing members and enclosing air spaces therebetween, said superimposed frames being joined together forming an insulating panel, said joined together frames being provided with means constituting said spacing members as sealing 30 means for preventing the ingress of air to the air spaces between the flexible material, said insulating panel being removable from and insertable into the space between the said walls as a unit.

14. An insulating structure including inner 35 and outer walls for substantially enclosing a space to be insulated, insulating means between

said walls, said insulating means including a plurality of independent self-sustaining frames arranged in the form of an unbroken perimeter of a polygon, said frames being superimposed one upon the other in alignment, flexible material having heat reflecting surfaces secured to and extending over the frames, said superimposed frames being joined together forming an insulating panel, said joined together frames being provided with means constituting sealing means 10 for preventing the ingress of air to the air spaces between the flexible material, said insulating means being removable from and insertable into the space between the said walls as a unit.

15. An insulating structure including inner 15 and outer walls for substantially enclosing a space to be insulated, insulating means between said walls, said insulating means including a plurality of independent self-sustaining frames, each of said frames consisting of self-sustaining spacing members arranged in the shape of an unbroken perimeter of a polygon, said frames being superimposed with the spacing members in alignment, flexible material having heat reflecting surfaces secured to said spacing members and enclosing air spaces therebetween, said superimposed frames being joined together forming an insulating panel, the said spacing members co-operating with one another to close the spaces between the flexible material, and means cooperat- 20 25 ing with said spacing members for sealing the said spaces between the flexible material to prevent the ingress of air to said spaces, said insulating unit being removable from and insertable into the space between the walls as a unit. 30 35

EDMUND F. SCHWELLER.
